UNITED STATES PATENT OFFICE.

DANIEL HARRIGAN, OF FRESNO, CALIFORNIA.

LOGGING BUNK.

Application filed May 18, 1926. Serial No. 109,871.

My invention relates primarily to a bunk for use in transporting logs by railway from the woods to the mills, although it is not limited to such specific use and may be used 5 upon motor trucks and the like for shipping pipe and other similar tubular or cylindrical material, and the prime object thereof is to provide a logging bunk which, while providing the maximum security for the materials 10 during transportation and the maximum safety for the operator while the logs or the like are being unloaded, will be simple in construction and operation and cheap to manufacture.

15 Another object is to provide a device of the above character which is equally applicable to new or old cars or vehicles and which can be easily and quickly mounted thereon without materially altering the same.

20 Other objects and advantages will appear hereinafter and, while I have shown and will describe the preferred form of my invention, it will be understood that I do not limit myself to such preferred form but that various changes and adaptations may be made 25 therein without departing from the spirit of my invention.

In the drawings accompanying and forming a part hereof:

30 Fig. 1 is a side elevation of my bunk detached from its place of use.

Fig. 2 is a top plan of Fig. 1, partly broken away.

Fig. 3 is a right hand elevation of Fig. 1.

35 Fig. 4 is a fragmentary side elevation of my bunk showing the method of releasing the blocks.

Fig. 5 is a fragmentary side elevation 40 showing the position of the block after being released.

Referring to the drawings my bunk comprises a base 6, preferably of wood upon the upper face of which is mounted a channel member 7 by means of bolts 8 or otherwise.

45 Formed in each end of base 6, centrally thereof, are recesses 9 and 10, which register with similar recesses 11 and 12 in the ends of channel member 7. A saddle 13 surrounds the lower ends of each of the recesses 9 and 10 and is secured to base 6 by bolts 14 and forms a socket for the reception 50 of the lower end of the holding blocks 15. Blocks 15 have their upper major portion of a width corresponding to the width 55 of the channel member 7 and their lower ends are sized to snugly fit the recesses 9

and 10, with the shoulders or abutments formed by reducing the width of the blocks resting upon the bottom of the channel member 7. Rigidly mounted upon the outer faces of the holding blocks 15 about midway of the length of the wider portion are upwardly opening hooks 16 and 17. Extending horizontally through base 6 near each end thereof are elongated openings 18 and 19 60 and pivotally mounted by means of pintles 20 and 21, within said openings about centrally of the width of base 6 are the securing members 22 and 23. Members 22 and 23 are substantially L-shaped in top plan and pintles 20 and 21 pass through one of the legs thereof about centrally of their length. The pivoted leg of members 22 and 23 project 65 from opposite sides of base 6 and the free ends terminate in apertured bosses 24 and 25. 70

The other ends of members 22 and 23 are connected to operating levers 26 and 27 which normally lie parallel with the sides of said base and extend therealong to the opposite end of base 6. Blocks 15 are connected to base 6 by short chains 28 and 29 which serve to retain the same against displacement or loss. Secured at one end to the sides of base 6 at the ends thereof and on opposite sides of said base are holding chains 80 30 and 31. Extending outwardly from opposite sides of base 6 just below the outer termination of the elongated openings 18 and 19 are eye bolts 32 and 33 and mounted at one end upon the eyes are the locking 85 hooks 34 and 35 adapted in cooperation with the apertured bosses 24 and 25 to lock the free ends of chains 30 and 31 to base 6 to hold blocks 15 in their operative positions. Secured at one end to the side of base 6 near 90 the ends thereof are chains 36 and 37 adapted to be brought to surround the free ends of operating levers 26 and 27 and have their free ends detachably mounted upon hooks 38 and 39 to secure said levers against movement.

100 In the operation of my bunk, it being understood that a car or other vehicle will be equipped with a bunk at each end and sometimes intermediate the ends, depending upon 105 the length of the car and the length of the material it is intended to handle, the parts will normally lie in the position shown in Figs. 1, 2 and 3. It will be noted that the holding chains 30 and 31 extend from their connection to base 6 around the outer sides of blocks 15 and over hooks 16 and 17 and

the free ends are then engaged by the locking hooks 34 and 35, the free ends of these hooks being positioned within the apertured bosses 24 and 25.

- 5 When it is desired to unload the load from the car or vehicle the operator will take his position at the opposite side of the car from which it is desired to unload. He will then release the chains 26 or 27 and move the 10 respective operating handle outwardly away from the side of base 6, which will rock members 22 and 23 and move the apertured boss from engagement with the end of locking hooks 34 and 35. The pressure of the 15 load will then force the upper end of block 15 outwardly withdrawing the end of the holding chain from hook 34 or 35. Continued pressure of the load upon block 15 will upset the same withdrawing the lower end 20 thereof from the saddle 13 and it will then fall to the limit of the short chains 28 or 29 out of the way of the falling logs.

By this construction I have provided a simple and very efficient logging bunk in 25 which the danger of injury to the workman is entirely eliminated due to the fact that the blocks or stakes are released from the side of the car opposite to that at which the stake is located and the load dumped off.

30 Having described my invention what I claim is:

1. In combination with a railway flat car a logging bunk therefor comprising a rectangular base mounted upon said car at 35 the end thereof; a substantially U-shaped channel member mounted upon said base to open upwardly, a recess in each end of said base and channel member centrally of the width thereof; a saddle surrounding the 40 lower end of said recess and forming a socket; elongated apertures passing through said base horizontally and transversely thereof; substantially L-shaped securing members pivotally mounted centrally of the length 45 of one of their legs in said apertures, the free end of said pivoted legs terminating in apertured bosses; operating levers secured at one end to the other leg of said securing members to normally lie parallel with said 50 base; locking hooks pivotally connected at one end to the side of said base in juxtaposition to said apertured bosses adapted to co-operate therewith to secure the free ends of said locking chains in operative positions; 55 a holding block loosely secured to the end of said base adapted to be mounted at its lower end in said recess and socket and be held positioned therein by said holding chain adapted when said chain is released 60 to fall from said socket and recess upon pressure from the load; and means to secure said operating handle against movement.
2. In combination with a railway flat car, a logging bunk therefor comprising a 65 rectangular base mounted upon each end thereof to extend transversely; a substantially U-shaped channel member mounted on said base opening upwardly a recess in each end of said base and channel member centrally of the width thereof a saddle 70 rounding and enclosing the lower end of said recess and forming a socket; elongated apertures passing transversely through said base horizontally thereof; securing members pivotally mounted in said apertures and projecting from each side of said base, said securing members being substantially L-shaped in top plan and being mounted reversely to each other the free end being pivoted centrally of the length of one leg, the free end 75 of said leg terminating in an apertured boss, the other leg extending parallel with said base; securing hooks mounted on said base adapted to have the free end thereof projecting into said apertured boss; holding blocks removably mounted in the recesses in the ends of said base and channel member and projecting above the same, the upper end of said blocks being of a width substantially equal to the width of said channel 80 member and supported thereby; upwardly opening hooks secured to the outer face of each of said blocks; securing chains connected at one end to the sides of said base 85 adapted to be passed around the outer face 90 of said blocks within said hooks and have the free ends engaged by said securing hooks; operating handles connected to the other leg of each of said securing hooks for operating the same; and means to lock said 95 operating levers against outward movement.
3. In combination a railway flat car, a bunk therefor comprising a rectangular base mounted at each end thereof to extend transversely its entire width; an upwardly 100 opening channel member mounted upon said base in substantial register therewith; a recess formed in the ends of said base and channel member; a saddle surrounding and closing the open side of said recess at the lower end thereof and forming a socket; a holding block mounted in each of said sockets to extend vertically above said base and channel, the lower end of said blocks being narrower than the upper end whereby supporting shoulders are formed to rest upon the upper face of said channel; an upwardly opening hook extending from the outer face of each of said blocks; elongated apertures 105 extending through said base near each end transversely thereof and on a horizontal plane; substantially L-shaped securing members pivotally mounted centrally of the length of one of their legs in said apertures 110 to project from each side of said base, the free end of said legs terminating in apertured bosses; securing hooks loosely mounted upon the sides of said base adapted to have their free ends engageable with the 115 apertures in said bosses; holding chains 120 to project from each side of said base, the free end of said legs terminating in apertured bosses; securing hooks loosely mounted upon the sides of said base adapted to have their free ends engageable with the apertures in said bosses; holding chains 125 to project from each side of said base, the free end of said legs terminating in apertured bosses; securing hooks loosely mounted upon the sides of said base adapted to have their free ends engageable with the apertures in said bosses; holding chains 130

cured at one end to the sides of said base near each end thereof on the side opposite said apertured bosses adapted to be passed around the outer faces of said holding blocks supported by said upwardly opening hooks and have their free ends engaged by said securing hooks; operating handles connected to the other leg of said securing members for rocking said members on their pivots to withdraw said bosses from engagement with said holding chains; and means for locking said operating handles against accidental movement.

In witness that I claim the foregoing I have hereunto set my hand this 21st day of 15 August, 1925.

DANIEL HARRIGAN.
